ELECTRICAL CONTROL CIRCUIT

Ellis Osmon Erickson, Pasadena, Calif., assignor
to Claude Neon Electrical Products Corpora-
tion, Ltd., Wilmington, Del., a corporation of
Delaware

Application May 15, 1933, Serial No. 671,055

9 Claims. (Cl. 176—124)

This invention relates broadly to the control of potentials in electrical circuits and has a particular application to the dimming of electric lamps and the flashing of gaseous discharge devices, 5 such as neon lamps. It is particularly useful for flashing purposes in connection with gaseous discharge lamp systems of the type disclosed in my copending application Serial No. 664,191, filed April 3, 1933, entitled Neon lamp circuit, in which 10 a special means is employed for starting the lamps.

A broad object of the invention is to vary the potential in a circuit carrying considerable power under the control of a circuit carrying only a relatively small amount of power without resorting to the use of relays or other devices having contacts in the power circuit. 15

Another object is to provide a transformer construction having power circuit windings capable of handling considerable power, and a control winding that needs handle only relatively small amounts of power for varying the output potential of the transformer through a wide range. 20

Another object of the invention is to extinguish the arc in a gaseous discharge device without making or breaking a circuit carrying any current of substantial magnitude or at substantial 25 potential, and without imposing excessive current upon any element of the lamp circuit.

Another object is to provide a very simple and effective method of flashing gaseous discharge lamps that are provided with starting equipment of the type disclosed in my aforementioned application Serial No. 664,191. 30

The application of the invention in connection with the flashing of gaseous discharge lamps may be briefly described as follows:

The gaseous discharge lamps most commonly used comprise elongated tubes filled with suitable gases at suitable pressure and having electrodes at opposite ends for supplying current to the gas column. These lamps, in operation, have negative resistance characteristics and for that reason are supplied with current from a circuit having substantial inductive reactance for regulation purposes. The regulating reactance may consist of a reactance element connected directly in series with the lamp, this arrangement being generally used when the lamp is operated at potentials less than the available line potentials; or it may be constituted by the leakage reactance of a transformer used to couple the lamp to the line, the latter arrangement being commonly employed when the lamp requires a potential greater than line potential. 45

There are several obvious ways of interrupt-

ing the flow of current through a gaseous discharge lamp in a circuit of the type described. One way is to open the supply circuit, but this entails the use of switch contacts capable of handling the total power delivered to the lamp and is objectionable for that reason. 5

Another way is to short-circuit the lamp but this is objectionable because the regulating reactance element in series with the lamp must then be designed to withstand full line potential; furthermore, the switch contacts must be capable of handling currents in excess of the normal lamp current. This method also wastes power due to the losses in the reactance element and imposes a load of low power factor on the line. 10

Another method would be to introduce an impedance in series with the lamp to reduce the lamp current to such a point that the lamp would not operate. However, the actual introduction of such an impedance in conductive relation in the 15 circuit would involve difficulties.

In accordance with the present invention, I introduce an impedance in series with the lamp to reduce the current in the lamp below a value sufficient to maintain the discharge by inductively 20 coupling an impedance to the lamp circuit instead of conductively connecting it thereto. In this manner the lamp may be extinguished without actually breaking the power circuit of the lamp. 25

My new method lends itself admirably to the 30 lamp-starting circuits of my application Serial No. 664,191, because those circuits are already provided with coils inductively coupled to the lamp supply circuits, which coils may be used for inductively introducing an extinguishing impedance into the supply circuit. Specific applications of the invention to gaseous discharge lamp circuits will be described in detail following the 35 analysis of the general circuit involved.

In the drawing:

Figure 1 is a schematic circuit diagram of a 40 transformer for supplying current to a load circuit with a special control winding on the transformer for varying the potential applied to the load;

Figure 2 is a schematic circuit diagram of a 45 system incorporating the invention for flashing a gaseous discharge lamp;

Figure 3 is a schematic circuit diagram of a 50 control system for a lamp energized directly from a pair of line terminals in series with a regulating reactance; and

Figures 4 and 5 are graphs explaining the 55 operation of the circuit shown in Figure 1.

Referring to Figure 1, I have shown a trans-

former designated generally at 1, having a closed magnetic core upon opposite legs of which are mounted a primary winding 4 and a secondary winding 5, and having a shunt core section upon 5 which is mounted a tertiary winding 3 for control purposes. The primary winding 4 is designed to be connected to a source of alternating current 8 and the secondary winding 5 is adapted to be connected through a switch 50 to a load circuit 10 indicated diagrammatically as an impedance 6. The tertiary winding 3 is shown connected to a variable impedance element 7. The load impedance 6 may consist predominantly of resistance and the control element may consist of a 15 resistance, a reactance, a capacitance, or a combination of such elements.

For convenience in describing the operation of 20 the transformer 1, the core section is divided by dotted lines into three sections, *a*, *b*, and *c*, respectively. It will be observed that the core sections *a* and *b* form a closed magnetic circuit, upon opposite legs of which the primary and secondary windings 4 and 5, respectively, are mounted and that the shunt core section *c*, together with the 25 air gap *d*, constitute a magnetic path in shunt to the respective magnetic paths comprising core sections *a* and *b* upon which the primary and secondary windings are positioned. Because of the relatively high reluctance of the air gap *d* the shunt path comprising the core section *c* and the air gap *d* in series offers a substantially higher 30 reluctance than the closed magnetic circuit comprising core sections *a* and *b*; therefore, when the secondary winding 5 is not drawing current (as when switch 50 is open) the major portion of the total flux developed in core section *a* by the magnetizing current in the primary winding 4 threads the core section *b*. Under the conditions outlined, the flux flowing through the core section *c* across 35 the air gap *d* may comprise only 10 per cent or less of the total flux developed in the core section *a*.

However, when the switch 50 is closed to 40 connect the load impedance 6 across the secondary winding 5, current flows in the secondary winding 5 and the direction of this current is such as to develop, or tend to develop, in the core section *b* a magnetic flux opposing the flux developed 45 by the primary winding 4. Under these conditions, a substantial flux is developed in the shunt core section *c* and this, in effect, introduces substantial leakage reactance effectively in series 50 with the secondary winding 5 so that the potential applied to the load impedance 6 is substantially less than the open circuit potential of the secondary winding 5.

Transformers of the general type described, having a shunt core section, are old in the art and have been used extensively for supplying 60 loads such as neon lamps which require a regulating reactance in series with the load. However to the best of my knowledge, in the prior known constructions there was no way of varying the amount of leakage reactance introduced effectively in series with the secondary winding except by changing the structure of the transformer, as for instance by varying the length of the shunt core section *c* to increase or decrease the length 65 of the air gap *d* and thereby vary the total reluctance of the shunt magnetic path.

In accordance with the present invention, I 70 have discovered that an effect substantially equivalent to that resulting from increasing or decreasing the length of the air gap *d* may be obtained by placing the tertiary winding 3 on the

shunt core section *c* and connecting the terminals of the tertiary winding to an impedance of specific characteristics. Thus I have discovered that if the load 6 is substantially resistive the current delivered to the load may be increased by employing a device having predominantly inductive reactance, as the element 7, the inductive load across the tertiary winding 3, in effect, increasing the air gap *d* and decreasing the leakage reactance of the transformer. If the impedance element 7 is capacitative a substantially different result is obtained, a very low capacitive reactance producing an increase in the output current of the transformer over that resulting when the winding 3 is open circuited, whereas higher capacitive reactance produces marked reductions in the output current as compared to the current supplied with the winding 3 open circuited. The general relation between transformer output current (when supplying a constant resistive load) and different pure reactance values for the impedance 7 shunted across the tertiary winding is shown by the curves of Figure 4 in which the ordinates represent current flow in amperes and the abscissæ represent the reactance in ohms of the impedance 7. In Figure 4 the ordinate of point 60 represents the magnitude of the output current when the tertiary winding 3 is short circuited (corresponding to zero value for impedance 7) and the ordinate of the horizontal dotted line 61 represents the magnitude of the output current when the tertiary winding 3 is open circuited (corresponding to infinite value for impedance 7). It will be observed that the curves for inductively reactive and capacitively reactive control impedances (impedance 7) asymptotically approach the line 61. It will also be observed that for various values of inductive reactance the output current is always greater than that obtained when the tertiary winding 40 is open circuited (the line 61), and varies relatively gradually with changes in the reactance. On the other hand, when the element 7 is capacitive reactive the output current changes 45 rapidly and except for very low values of reactance the output current is less than the current (line 61) when the tertiary winding is open circuited. Obviously, when utilizing a capacitive reactance it is desirable to so proportion it as to 50 utilize the sharply falling portion of the curve for reducing the transformer output current.

The curve of Figure 5 shows the relation between transformer output current to a resistive load 6 and varying values of pure resistance used as the control impedance 7. It will be observed that as the resistance is increased from zero (the short circuit condition of winding 3) to higher values the output current drops fairly rapidly to a value appreciably less than the value under open circuit condition (represented by line 61), and then very gradually increases asymptotically toward the open circuit value. Although the current curve for a pure resistance tertiary coil loading shows what might be considered very little control effect over any useful range, it actually is sufficient when the load 65 comprises a gaseous discharge tube or lamp to reduce the current in the tube sufficiently to extinguish the tube.

An important advantage of the circuit shown 70 in Figure 1 is that the control impedance element 7 may be located at a point remote from the transformer 1. Furthermore, I have discovered that the tertiary winding 3 and the control impedance 7 may be designed to be built at low 75

cost as they are required to handle only relatively small amounts of power compared to the power consumed by the load impedance 6, which power must, of course, be handled by the primary and 5 secondary windings 4 and 5, respectively.

Referring now to Figure 2, I have shown a gaseous discharge lamp 10 having a pair of electrodes 11 and 12, respectively, adapted to be heated from any convenient source of current.

10 The electrode 11 is shown connected to one conductor 13 of a three-wire supply circuit which may provide a potential of 220 volts between the two outside conductors 13 and 15 and a potential of 110 volts between either of the outside conductors 13 and 15 and a neutral conductor 14. The other terminal 12 of the lamp 10 is connected to one end of a high potential secondary winding 16 of a transformer 17. Transformer 17 is of the type previously described in connection with Fig. 15 1 having, in addition to the secondary winding 16, a primary winding 18 and a tertiary winding 19 on a shunt core section of the transformer. The primary winding 18 is connected across the line conductors 14 and 15, as shown, and the 20 opposite end of the secondary winding 16 is also connected to the line conductor 15 so that the total potential impressed upon the lamp 10 is the sum of the line potential between the line conductors 13 and 15 and the potential developed 25 in the secondary winding 16.

30 The lamp 10 is of a type that is incapable of automatically starting in response to application of the normal operating potential thereto. For this reason, a starting device 20 is provided for 35 initiating a discharge in the lamp. This starting device may comprise a spark coil adapted to be energized by a 110-volt current and to produce a high frequency discharge which is applied over a conductor 21 to an electrode 22 positioned adjacent the lamp 10. Starting devices of this 40 type are old and well-known in the art, and need not be described in detail herein.

45 The spark coil 20 is provided with energizing potential by connecting one of its input terminals to the junction point 23 of a reactance element 24 and a resistance element 25 connected in series across the line conductors 13 and 15; and connecting the other input terminal through a switch contact 26, a switch arm 27 and the 50 tertiary winding 19 to conductor 15.

55 A second switch contact 28 is connected through an impedance element 29 (corresponding in function to the impedance element 7 in Figure 1) to that end of the tertiary winding 19 which is connected to the line conductor 15.

60 The circuit described functions as follows: Assume that the switch arm 27 is in mid position out of engagement with both contacts 26 and 28 and that the line conductors 13, 14 and 15 are energized. Under these conditions, the secondary winding 16 of the transformer 17 will develop its full open circuit potential and this potential will be applied in series with the line potential across the terminals of the lamp 10. However, 65 the lamp will not start without special excitation and this excitation is provided by shifting the switch arm 27 to close on contact 26. Because of the fact that the reactance element 24 and resistance element 25 are so proportioned as to develop a substantial potential drop across the reactance element 24, the point 23 is maintained at a substantially constant potential different from the potential of conductor 15 by a substantial amount, and out of phase therewith. 70 This constant potential developed at the junc-

tion point 23 is constantly applied to one input terminal of the starting device 20. With the switch arm 27 closed upon contact 26, the other input terminal of the starting device 20 is connected through the tertiary winding 19 to the line conductor 15. Because of the fact that, with the lamp 10 not operating, the secondary winding 16 of the transformer is drawing no current, only a very small portion of the flux developed in the transformer core by the primary 10 winding 18 passes through the shunt core section. Therefore, when the lamp is not operating, only a negligible potential is developed in the tertiary winding 19 and the potential applied through the contact 26 to the input terminal of the starting device 20 is substantially that of the line conductor 15. Therefore, substantial potential is applied to the input terminals of the starting device 20 and the latter is actuated to develop high frequency impulses which are applied to the 15 electrode 22 and start the discharge in the lamp 10.

20 Of course, as soon as the lamp 10 begins to operate, it draws current from the secondary winding 16 of the transformer and the current 25 flow in winding 16 tends to produce a flux opposing that produced by the primary winding 18 with the result that a substantial flux is produced in the shunt core section upon which the tertiary winding 19 is positioned. Therefore, 30 with the lamp operating, a substantial potential is developed in the tertiary winding 19 and this winding is so dimensioned and poled as to produce at the input terminal of the starting device 20 connected thereto through contact 26, a potential substantially equal in phase and magnitude to the potential of the junction point 23. Therefore, the starting device ceases to function 35 as soon as the lamp 10 starts operation. Circuits of the general type described, including a tertiary 40 winding on the lamp transformer for controlling the operation of the starting device, are fully discussed in my copending application, Serial No. 664,191, previously referred to, and a full explanation of the theory of operation of such circuits for starting purposes is given therein. 45

When it is desired to extinguish the lamp 10, the switch arm 27 is thrown from contact 26 to contact 28. This connects the impedance 50 55 element 29 either a capacity reactance element or a resistance element, directly in shunt to the tertiary winding 19 and has the effect of decreasing the output current from winding 16 of the transformer in the manner previously described in connection with Figure 1. This decrease in current reduces the total current supplied to the lamp 10 and by suitably proportioning the impedance element 29 relative to the tertiary winding 19 the reduction in the current may be made of sufficient magnitude to extinguish the lamp 10. Immediately the lamp is extinguished, it ceases to draw current from the secondary winding 16 and this, in turn, reduces the flux in the shunt core of the transformer to its original value and, of course, decreases the 60 potential developed in the tertiary winding 19 to a negligible value so that if desired the switch arm 27 may be left against contact 28 without producing any appreciable energy loss in the tertiary winding 19 and the impedance element 29, 65 or the contacts may be broken without appreciable sparking because of the low voltage developed. 70

75 It will be observed from the foregoing description that the lamp 10 may be started at 75

will by shifting the switch arm 27 into engagement with contact 26 and extinguished by shifting the switch arm into engagement with contact 28. Obviously, if desired, the switch arm 27 may be constituted by the armature of a relay or by any automatic mechanical switching device for closing the two circuits alternately at any desired intervals to automatically flash the lamp 10.

10 The system of Figure 2 just described related to the operation of a lamp requiring potential greater than line potential, in which case the necessary high potential could only be obtained by the use of a transformer. In Figure 3 my invention is shown applied to the flashing of a lamp which is capable of operating at potentials less than line potentials. In Figure 3 I have shown a lamp 30 having a pair of electrodes 31 and 32, respectively, adapted to be heated from any desired source of current and connected in series with the winding 33 of a regulating reactance across line conductors 34 and 35. In this instance, the regulating reactance is provided solely for controlling the flow of current through the lamp 30 when the latter is operating, such a controlling impedance in series with the lamp being required because of the negative resistance characteristic of the lamp. A starting device 36 is provided for starting the lamp 30 and has a pair of input terminals connected respectively to a contact 37 and the junction point 38 of a reactance element 39 and resistance element 40 connected in series across the line conductors 34 and 35. A switch arm 41, adapted to be moved into and out of engagement with the contact 37, is connected to one end of an auxiliary winding 42 on the same core as the winding 33 and closely coupled thereto. The other end of winding 42 is connected to line conductor 34 and is also connected through a control impedance 43, which is either capacitively reactive or resistive, to the other contact 44 associated with the switch arm 41.

45 The circuit of Figure 3 functions substantially the same as that of Figure 2. Thus, when the switch arm 41 is moved into engagement with contact 37 substantial voltage is supplied to the starting device 36 because of the fact that the junction point 38 is at a potential substantially different from the potential of line 34, whereas the switch arm 41 is then substantially at the same potential as line 34 because of the fact that the lamp 30 is drawing no current through winding 33 and, therefore, no potential is induced in the auxiliary winding 42. When the lamp starts, it immediately draws current through the winding 33 of the regulating reactance and this flow of current induces a potential in winding 42. Winding 42 is so proportioned and poled as to develop a potential substantially equal in magnitude and phase to the potential drop across the reactance element 39 so that the potential applied to the starting device 36 after the lamp 30 has started is reduced to a negligible value and the starting device ceases to function.

55 When it is desired to extinguish the lamp 30, the switch arm 41 is moved out of engagement with contact 37 and into engagement with contact 44, thereby connecting the control impedance 43 across the winding 42. I have found that the effect of connecting the capacitively reactive or resistive impedance 43 across the winding 42 is to increase the impedance of the winding 33 and by suitably proportioning the impedance element 43 the effective impedance of winding 33 may be

increased sufficiently to decrease the current in the lamp below the value necessary to support the arc, whereupon the lamp is extinguished. With the lamp extinguished, the current in winding 33 falls to zero. This is a desirable feature because it means that the impedance element 43 need be designed to handle only currents of very short duration. Furthermore, when the switch arm 41 is subsequently moved from contact 44 to contact 37 to again start the lamp 30, there is no arc at contact 44 since no current is flowing in its circuit at that time.

5 Numerous variations in the specific circuit shown may be introduced without departing from the essential principles disclosed, and the invention is, therefore, to be limited only as set forth in the appended claims.

I claim:

1. In combination, a source of A. C. potential; a non-self-starting gaseous discharge device having high impedance when not operating, a lower impedance when operating, and requiring current in excess of a predetermined value to maintain it in operation; means for supplying operating current from said source to said discharge device comprising a transformer having first and second core sections constituting a closed magnetic circuit of low reluctance, and a third core constituting a magnetic circuit of relatively high reluctance in shunt to said first and second sections, said first core section having a primary winding thereon connected to said source, said second core section having a secondary winding thereon connected to said discharge device, and said third core section having a control winding thereon; and a switch and impedance element connected in series with said control winding for decreasing the current supplied to said discharge device below said predetermined value in response to closure of said switch.

2. In combination, a source of A. C. potential; a non-self-starting gaseous discharge device having high impedance when not operating, a lower impedance when operating, and requiring current in excess of a predetermined value to maintain it in operation; means comprising an inductive winding in series with said device for supplying operating current to said device from said source; a terminal, and means connected to said source for deriving therefrom a substantially constant reference potential and applying it to said terminal; a control winding inductively coupled to said first winding and connected at one end to one side of said source, said control winding being so proportioned and poled as to have induced therein, when said gaseous discharge device is drawing operating current through said inductive winding, a potential substantially equal to said reference potential; a starting device having input terminals for initiating a discharge in said gaseous discharge device in response to potential applied to its input terminals; an impedance element; and switch means for alternately connecting said impedance element in shunt to said control winding to reduce the current supplied to said discharge device below said predetermined value, and connecting the input terminals of said starting device between the free end of said control winding and said terminal to start said discharge device.

3. A system as described in claim 2 in which said means for deriving the reference potential of constant value comprises a reactance element and a resistance element connected in series across said source, and said terminal is connected

to the junction between the reactance element and resistance element.

4. In combination, a source of A. C. potential; a non-self-starting gaseous discharge device having high impedance when not operating, a lower impedance when operating, and requiring current in excess of a predetermined value to maintain it in operation; means comprising an inductive winding connected in series with said device across said source of potential for supplying operating current to said device from said source; a control winding inductively coupled to said first winding and connected at one end to one side of said source, said control winding being so proportioned and poled as to have induced therein, when said gaseous discharge device is drawing operating current through said inductive winding, a potential substantially equal to said reference potential; a starting device having input terminals for initiating a discharge in said gaseous discharge device in response to potential applied to its input terminals; an impedance element; and switch means for alternately connecting said impedance element in shunt to said control winding to reduce the current supplied to said discharge device below said predetermined value, and connecting the input terminals of said starting device between the free end of said control winding and said terminal having the constant potential applied thereto, to start said discharge device.

5. In combination, a source of A. C. potential, a non-self-starting gaseous discharge device having high impedance when not operating, a lower impedance when operating, and requiring current in excess of a predetermined value to maintain it in operation; means for supplying operating current from said source to said discharge device comprising a transformer having first and second core sections constituting a closed magnetic circuit of low reluctance, and a third core section constituting a magnetic circuit of relatively high reluctance in shunt to said first and second sections, said first core section having a primary winding thereon connected to said source, said second core section having a secondary winding thereon connected to said discharge device, and said third core section having a control wind-

ing thereon; a terminal, and means connected to said source for deriving therefrom a substantially constant reference potential and applying it to said terminal; said control winding being connected at one end to one side of said source and being so proportioned and poled as to have induced therein, when said gaseous discharge device is drawing operating current from the secondary winding of said transformer, a potential substantially equal to said reference potential; a starting device having input terminals for initiating a discharge in said gaseous discharge device in response to potential applied to its input terminals; an impedance element; and switch means for alternately connecting said impedance element in shunt to said control winding to reduce the current supplied to said discharge device below said predetermined value and connecting the input terminals of said starting device between the free end of said control winding and said terminal, to start said discharge device.

6. In a system for supplying variable current to a load circuit, a transformer comprising first and second core sections constituting a closed magnetic circuit of low reluctance, and a third core section constituting a magnetic circuit of relatively high reluctance in shunt to said first and second sections, said first core section having a primary winding positioned thereon adapted to be energized from a source of A. C. potential, said second core section having a secondary winding thereon for supplying current to a load circuit and said third core section having a control winding thereon, a control impedance, and means for connecting said control impedance in shunt to said control winding for controlling the current and potential delivered by said secondary winding to the load.

7. A system as described in claim 6 in which said control impedance consists of a resistance element.

8. A system as described in claim 6 in which said control impedance consists of an inductive reactance element.

9. A system as described in claim 6 in which said control impedance consists of a capacitative reactance element.
